JOSEPH M. BUCHANAN, OF FREEPORT, NEW YORK.

METHOD OF MAKING SETS OF ARTIFICIAL TEETH.

Application filed March 4, 1924. Serial No. 696,859.

To all whom it may concern:

Be it known that I, JOSEPH M. BUCHANAN, a citizen of Canada, and resident of Freeport, in the county of Nassau and State of New York, have invented a new and Improved Method of Making Sets of Artificial Teeth, of which the following is a full, clear, and exact description.

This invention relates to mechanical dentistry and has particular reference to an improved method or process of making an integral set of artificial teeth and supporting plate.

Among the objects of the invention is to provide a method of making a combined set of teeth and plate of one piece of plastic material such as porcelain, so that the finished plate shall have a size and form to precisely fit the mouth cavity and without a permanently attached sheet or plate of metal.

With the foregoing and other objects in view the invention comprises or relates to a series of steps substantially as hereinafter more fully described and claimed, and I wish it to be understood, however, that the spirit of the invention is to be interpreted sufficiently broadly to embody certain variations in any of said steps.

For the purpose of illustrating a practical embodiment of the invention reference is had to the accompanying drawings, in which like reference characters designate the same parts in the several views, and in which—

Figure 1 is a perspective view indicating a conventional form of means for taking the impression of the mouth cavity.

Fig. 2 is a vertical transverse section of the same on the line 2—2.

Fig. 3 is a similar view illustrating the next step of the process.

Fig. 4 is a view indicating a succeeding step, namely the formation of the positive cast or model.

Fig. 5 is a cross sectional view of the model detached from the device as shown in Fig. 3.

Fig. 6 indicates the next step in the process in the applying of a sheet of metal or the like to the positive cast.

Fig. 7 is a perspective view of the plate shown in Fig. 6 ready for the molding thereon of the plastic material to form the set of teeth and integral plate; and

Fig. 8 is a vertical transverse section

through said plate and metal base on a plane corresponding to the lines 8—8 of Fig. 7.

Referring now more particularly to the drawings I show in Fig. 1 the process and means for forming an impression of the mouth cavity to be fitted. Ordinarily this process involves the use of a metal shell 10 having a shank 11 and adapted to contain a body or mass of plastic material 12 of any suitable nature which after the impression is made is adapted to harden sufficiently to serve to reproduce other devices having forms corresponding to that of the mouth cavity. For convenience of this description I shall refer to this member 12 as the negative cast.

While the negative cast is still supported in the shell 10 and thereby held sufficiently firmly for this purpose, the surface 12' thereof, constituting a counterpart of the mouth cavity, is filled or coated with a thin layer 13 of some suitable plastic material such as paint, varnish, shellac or the like of substantially uniform thickness.

With the filled negative cast as shown in Fig. 3 thus provided, it is used as a mold for a positive cast or mold 14 formed therein as shown in Fig. 4. This positive cast may be made of plaster of Paris or any other suitable plastic material having a fair degree of rigidity when set. The positive cast 14, shown detached in Fig. 5, is in the next step of the process turned over and has applied to its active surface 14' a layer of some suitable refractory metal 15, such as platinum or its equivalent.

The cast 14 as formed is smaller than the mouth cavity by the thickness of the filler 13. By applying the metal coating 15 of a thickness equal to the thickness of the filler, or in other words by making the filler of a thickness corresponding to that of the metal to be used on the positive cast, I produce the outer surface 15' of the plate 15 to constitute an exact counterpart of the mouth cavity. This plate 15 is then used either detached or in connection with the positive cast 14 supporting it as a base upon which is molded the plate 16 and teeth 17 integral therewith all from a single mass or body of plastic material such as porcelain.

The portion of the plate 16 representing the gum may be tinted as is well known in the art either before or after the baking thereof. With the mass of teeth and plate 16 attached thereto still supported upon the plate 15 it is subjected to a suitable

baking process and thereafter the platinum 15 is stripped or otherwise removed from the finished plate 16. The surface of the plate formed in contact with the surface 15' 5 of the platinum will then be precisely of the size and form of the mouth cavity. The platinum may be used repeatedly as many times as may be desired inasmuch as it is not employed as a permanent part of the teeth 10 or plate.

I claim:

The herein described method of making artificial teeth which comprises the following steps: (1) the making of a negative 15 cast bearing an exact impression of the mouth cavity; (2) the coating of the ac-

tive surface of said negative cast with a thin filler of temporary plastic material of uniform thickness producing thereby a filled negative cast; (3) forming a positive cast 20 or model in said filled negative cast; (4) forming upon said positive cast a layer of refractory metal of substantially the thickness of the filler applied to the negative cast, thereby producing a surface the exact counterpart of the mouth cavity; (5) then moulding upon said metal surface a set of teeth and attached plate; (6) baking said teeth and plate while supported upon said metal surface, and finally removing the 25 metal from the baked teeth and plate.

JOSEPH M. BUCHANAN.
